Primary Examiner — Natasha Vujcic

(57) **CLAIM**

The ornamental design for a mobile air conditioner, as shown and described.

DESCRIPTION

The patent or application file contains at least one drawing executed in color. Copies of this patent or patent application publication with color drawing(s) will be provided by the Office upon request and payment of the necessary fee.

1. Mobile air conditioner

1.1 : Front

1.2 : Back

1.3 : Left

1.4 : Right

1.5 : Top

1.6 : Bottom

1.7 : Perspective

The use of the present design product: the design product is used to adjust the air temperature; the design gist of the present design product: the shape of the product; the picture or photo best showing the design gist of the present design product: perspective view.
